UNITED STATES PATENT OFFICE.

CHARLES W. DONALDSON, OF AKRON, OHIO.

CONCRETE SHIP CONSTRUCTION.

1,377,153.

Specification of Letters Patent.

Patented May 3, 1921.

Application filed January 3, 1918. Serial No. 210,182.

To all whom it may concern:

Be it known that I, CHARLES W. DONALDSON, a citizen of the United States, residing at Akron, in the county of Summit and 5 State of Ohio, have invented certain new and useful Improvements in Concrete Ship Constructions, of which the following is a specification.

These improvements have to do with 10 ship construction utilizing as its structural material reinforced concrete.

The employment of such material for floating bodies is not new but the prior uses of concrete for this purpose have been necessarily limited by reason of the inability to 15 overcome the difficulties of compensating for the peculiar stresses to which such objects are subjected, as well as the disadvantages arising from the weight of the 20 material and resultant excessive displacement of the vessel where attempt is made to compensate for the stresses referred to by increasing the thickness of the structural parts.

25 Even in the restrictive use or adaptations of this material which so lends itself to economy and speed of construction, it has been necessary to utilize temporary form work, requiring skilled labor for carpentry 30 and large quantities of lumber, progress of building being obviously very slow, however, so as to render it impracticable as construction material for the purpose of providing floating bodies with reasonable swiftness and 35 with unskilled labor, especially where they are of large carrying capacity.

I overcome these disadvantages by so arranging the reinforcing material as to constitute the only required form producing means 40 whereby a monolithic wall, beam and column structure is produced, such reinforcement becoming a permanent part of the body, and the peculiar shaping of which involves the principle of arch construction, so adequately designed to resist both the tensile 45 and compressive stresses peculiar to ships.

By virtue of the design utilized I am able to provide a double wall or hull construction of cellular type and a floor or deck 50 relatively thin considering its weight sustaining requirements, so that the ratio of

weight to displacement under my method will not exceed the similar ratio in steel.

Hitherto in carrying this idea of construction into practice so much structural 55 iron or steel has been employed as to greatly detract from any advantages derived from using concrete. On the other hand I am able to dispense with heavy reinforcing elements solely by reason of the use of the arch 60 or dome formation principle which so distributes or equalizes the weight as to eliminate necessity for use of forms and to prevent breaking down of the given shape or 65 form of the foraminous reinforcing material I employ.

To this end the invention consists in the construction, combination and arrangement of parts all as hereinafter more fully described, claimed and illustrated in the accompanying drawings wherein:

Figure 1 is a fragmentary sectional view of a hull, a portion of the outer hull wall or section being broken away to show more clearly the cellular formation;

Fig. 2 is an enlarged horizontal sectional view of a section of the hull;

Fig. 3 is a similar view taken at right angles to the plane of the section in Fig. 2;

Fig. 4 is a sectional view of a modified 80 form of hull construction;

Fig. 5 is a vertical sectional view of the ship construction;

Fig. 6 is a horizontal sectional view of the column support; and

Figs. 7 and 8 are perspective views of the preferred forms of reinforcing material used in this construction.

Referring to the drawings and briefly describing the method of construction of ships 90 contemplated by me, I first dispose the outer and inner fabricated walls of the hull in the desired spaced relation to each other as indicated at 1 and 2 respectively. These walls consist of any desired type of metal lath or 95 expanded metal reinforcing material, though preferably containing in their structure suitable stiffening means such as rods whereby said reinforcing material maintains its given shape. In Fig. 8, for example, 3 100 designates the expanded metal or foraminous material and 4 the stiffening rods at-

tached thereto by loops 5 pressed from the material or by clipping the rods in place in any well known manner. The rods 4, as will be observed particularly in Fig. 5, run longitudinally of the boat and are designed to assist in resisting the tensile stresses. These spaced walls run up in parallel relation to the approximate height of the deck where the deck formation is started. At 10 this point the reinforcing material curves inwardly from the inner wall upon an arc as indicated at 6 and in this arch formation I preferably employ somewhat stiffer reinforcing material than that above described. 15 For instance, in Fig. 7 is disclosed the preferred form of reticulated material, having V-shaped ribbing, indicated at 7, and at the apex of the V-shaped ribs steel rods 8 are connected similarly to that described with 20 regard to the form of material shown in Fig. 8. In each instance the rods are exposed so that they will be surrounded by and united with the concrete material in the manner hereinafter described. If preferred, 25 the V-shaped material may be suitably provided with a fiber backing 9 which will constitute the protective covering for the reinforcing material on those interior surfaces where it is impracticable to apply a cement 30 coating.

Interposed between the inner and outer walls 1 and 2 are cavity producing members acting as forms which constitute a very essential feature of this invention. Referring 35 to Figs. 2 and 3 it will be observed that these cavity forms are elliptical in horizontal cross section and are arranged in spaced relation, the fabric or metal lathing being suitably tied in place by means of ties 10 attached to the walls 1 and 2 or to vertical rods 11 which are arranged between the said hull walls and the cavity forms. The top 40 of the cavity forms is arched not only transversely but also in a longitudinal direction, 45 as shown in Fig. 3, thus producing what I call an arch or dome formation.

As shown in Fig. 5 the arching of the cavity in the transverse direction as indicated at 12 conforms substantially to the 50 arching indicated at 6 and the reinforcing material is additionally tied as the formation of the wall proceeds by certain ties 13 which are connected to reinforcing rods 14 extending longitudinally of the boat in the 55 spandrels between the interior arches of the ship walls hereinbefore described. As the disposition of these reinforcing materials proceeds the concrete is poured into the space between the inner and outer reinforcing wall members 1 and 2 at points between the contiguous ends of the cavity forms what I term the interior beam and column or ribs of the hull. The concrete furthermore, in the deck formation progresses along with 60 the wall formation so that I obtain a per-

fectly monolithic structure when the ship is completed.

As observed in Figs. 1 and 5, at suitable intervals are arranged columns 15 which are produced by the arrangement of reinforcing material in circular configuration as shown in Fig. 6 at 16, said material having vertical reinforcing rods 17 connected thereto. The concrete is poured into such forms preferably, and subsequently the columns 75 are given an outer coating of concrete as is also true of both the inner and outer hull walls. It is to be understood that in following this method of construction the metal reinforcing material may be given 80 the exterior coating of concrete preliminary to the filling, or the filling may be preliminarily carried out and the outer concrete coating subsequently applied. At any rate as the wall of the hull progresses in formation I preferably give the interior surface of the cavities a coating of concrete also, which may be done by manual application or gunning in the well known manner so that the metal will be entirely embedded 85 within the concrete material and thus preventing the water from affecting the metal and causing deterioration within the concrete structure.

The reinforcing material, it will be understood, is arranged in arch formation from the column toward the walls and from column to column so that there exists a continuity of the arch construction throughout the entire formation of the structural parts of the vessel. Between column and wall or column and column the reinforcing material is suitably shored up temporarily by supports arranged at intervals so as to assist the arch and walls in sustaining the weight of the 105 material until thoroughly set. This shoring does not partake of any temporary or removable form structure whatever, this being entirely unnecessary in my type of construction. The deck or floor slab of concrete is poured upon the metal reinforcing until the proper depth is obtained and by reason of the combined arch and beam formation I am able to use a thinner floor slab than would be possible with any other usual beam and column or beam and wall formation not embodying the arch principle. 110

At this point it is to be noted that the cavity forms are so arranged in the ship walls as to lie between the planes of the decks 120 and coincide in disposition further with the transverse arrangement of the reinforcing materials for the deck supports. In other words, the interior structure of the ship walls is itself a beam and column or beam and wall construction, that part of the concrete filling indicated at 18 in Fig. 2 being in alignment with the column arrangement between decks. The portions 18 in a vertical plane extend continuously from the 125 130

upper deck to the keel of the ship, thus forming ribs, and in the formation of the floor beams which are best shown at 18' in Fig. 1 the continuity of construction is also 5 employed so that these beams provide transverse and longitudinal ribs. From this it follows that the stresses which are sustained by the ship in the transverse direction are transmitted from the outer hull 10 wall through the deck beam and column elements which are throughout of the arch formation and thus best adapted to properly equalize the stresses transmitted thereto. In exactly the same manner, speaking with 15 reference to a longitudinal section of the boat the stresses along longitudinal lines are transmitted from end to end of the ship by reason of the peculiar arch formation of the walls and decks. Having in view the 20 utilization of the longitudinal reinforcing rods 4 and 14 and the arch formation hereinbefore described, a ship constructed in accordance with my method is best adapted to sustain the tensile and compressive 25 stresses to which ships are particularly subjected and regardless of the rapidity with which a reversion of these stresses takes place.

In Fig. 4 the interior hull formation is 30 slightly different from that shown in Figs. 2 and 3 and being particularly adapted for ships of smaller capacity or size where the strength of the walls of the hull may be decreased. In this formation the air spaces 35 or cavities in the hull are formed by using a reinforcing material which in horizontal section is semi-elliptical.

It is notable that interior form producing 40 material, which is also a reinforcement, is curved on a radius substantially bisecting the angle between the hull wall and deck whereby to form an arched support at the juncture of the deck and wall. Also as regards the hull wall, said wall may be characterized as of double construction so formed 45 as to produce therein longitudinal and transversal beams between the wall elements, said beams forming compartments embodying vertical side walls arched fore and aft, 50 end walls arched transversely, and top walls arched transversely and longitudinally. The bottom wall is of course flat.

Having thus described my invention, what I claim as new is:

55 1. A boat construction of the class described comprising a monolithic hull wall, beam and column construction having embedded therein foraminous reinforcing material initially constituting the form producing means for the boat and forming a permanent part of the structure, the interior outlines of said reinforcing material at the junctures between the walls, beams and columns being curved to form arching supports.

2. A boat of the class described comprising a wall construction of reinforced concrete, the wall being provided with cavities in the upper interior outline of which cavities and deck is arched in conformation. 70

3. A double walled concrete craft so formed as to provide longitudinal and transverse beams between the wall elements, whereby to form compartments, the vertical side walls of which are arched fore and aft, 75 the end walls arched transversely, and the top walls arched transversely and longitudinally.

4. A concrete craft substantially as claimed in claim 3, wherein the said compartments 80 are formed by cavity producing members of reinforcing material, said members being disposed between the wall elements so as to permit of concrete being disposed in such a manner as to embed these members in the 85 double wall structure.

5. A boat of the class described comprising a monolithic concrete hull and deck of beam and column formation, the hull having cavities therein also of beam and column 90 formation and coinciding with the similar formation of the deck, the forms aforesaid being arched in both transverse and longitudinal directions.

6. A boat of the class described comprising a hull of reinforced concrete, said hull having cavity producing forms arranged in spaced relation, the interior outline of the cavities being arched in both directions of the ship. 95

7. A boat of the class described comprising a hull of reinforced concrete, said hull having dome shaped cavities within the wall thus forming an inner and outer "skin." 100

8. The method of constructing reinforced concrete hulls of ships which consists in placing an outer wall of reinforcing material in the desired position and an inner wall of such material in spaced relation thereto, interposing between such walls spaced cavity 110 producing forms and tying said forms and walls together, and finally filling in between the walls and between the cavity forms with concrete whereby to produce a cellular hull of beam and column construction. 115

9. The method of constructing reinforced concrete hulls of ships which consists in placing an outer wall of reinforcing material in the desired position and an inner wall of such material in spaced relation thereto, interposing between such walls spaced cavity producing forms and tying said forms and walls together, filling in between the walls and between the cavity forms with concrete whereby to produce a cellular hull of beam 120 and column construction, and then coating the outer surfaces of the walls so as to entirely embed the reinforcing material in the walls. 125

10. A boat construction of the class de- 130

scribed comprising a monolithic hull wall, beam and column construction having embedded therein foraminous reinforcing material initially constituting the form producing means for the boat and forming a permanent part of the structure, the interior outlines of said reinforcing material at the

junctions between the walls, beams and columns being curved to form arching supports, and stiffening members attached to the foraminous material for holding said material in the given shape.

In testimony whereof I affix my signature.

CHARLES W. DONALDSON.
